(57) **CLAIM**

The ornamental design for a kippah case with domed insert, as shown and described.

DESCRIPTION

FIG. 1 is a front perspective view of a first embodiment of the kippah case with domed insert design with the case in a partially open position.

FIG. 2 is a front perspective view of the design with the case in a fully open position.

FIG. 3 is a top view of the design with the case in a fully open position.

FIG. 4 is a right side view of the design, with the case in a fully open position of the design. The left side view is a mirror image thereof.

FIG. 5 is a bottom view of the design with the case in a fully open position.

FIG. 6 is a front view of the design with the case in a fully open position; and,

FIG. 7 is a rear view of the design with the case in a fully open position.

The broken lines showing a zipper pull and teeth, and interior strap and an exterior handle, are included for the purpose of illustrating portions of the kippah case with domed insert that form no part of the claimed design.
